US00D943576S

(12) **United States Design Patent** (10) Patent No.: **US D943,576 S**
Bristol et al. (45) Date of Patent: **** Feb. 15, 2022**

(54) **HEAD-MOUNTED DISPLAY**

(71) Applicant: **Facebook Technologies, LLC**, Menlo Park, CA (US)

(72) Inventors: **Peter Wesley Bristol**, Seattle, WA (US); **Joseph Patrick Sullivan**, Seattle, WA (US); **Mauricio Romano**, Redmond, WA (US); **David Michael Pickett**, Seattle, WA (US); **Peter Allan Chase Newbury**, Burlington, WA (US); **Quintin Morris**, Seattle, WA (US); **Shane Michael Ellis**, Bellevue, WA (US); **Glen Jason Tompkins**, Woodinville, WA (US); **Enric Vial Roig**, Seattle, WA (US); **Joel Bernard Jacobs**, Seattle, WA (US)

(73) Assignee: **Facebook Technologies, LLC**, Menlo Park, CA (US)

(**) Term: **15 Years**

(21) Appl. No.: **29/796,987**

(22) Filed: **Jun. 28, 2021**

CLAIM

The ornamental design for a head-mounted display, as shown and described.

DESCRIPTION

FIG. 1 is a front perspective view of a head-mounted display showing the claimed design;

FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

The broken lines shown in the figures illustrate portions of the head-mounted display that form no part of the claimed design.

1 Claim, 8 Drawing Sheets
